CORE TAKING APPARATUS

Fred Thrift, Campbellton, Tex.

Application March 27, 1933, Serial No. 663,054

3 Claims. (Cl. 255—72)

This invention relates to core taking apparatus.

An object of the invention is to provide apparatus of the character described for taking cores or samples of the formation encountered during well drilling operations and embodies a core barrel with novel means whereby the same may be securely landed in position in, and securely maintained in position in, the drilling apparatus.

Another object is to provide novel means for locking the core barrel in position which may be readily released when it is desired to withdraw the core barrel.

A further object is to provide, in a device of the character described, a novel construction whereby the drilling fluid may be utilized to force the core barrel into its final position in the drill stem and drill and whereby the pressure of the drilling fluid is released when the core barrel has landed in home position to indicate to the operator that the apparatus is in position for taking a core or sample.

Another object of the invention is to provide a sample taking device that may be readily lowered into and withdrawn from the drilling apparatus without withdrawing said drilling apparatus from the well.

With the above and other objects in view the invention has particular relation to certain novel features of construction, operation and arrangement of parts an example of which is given in this specification and illustrated in the accompanying drawing wherein:

Figure 1 shows a fragmentary vertical sectional view of a drill stem showing the upper end of the core taking apparatus therein.

Figure 2 shows a vertical sectional view of the intermediate portion thereof, and

Figure 3 shows a vertical sectional view of the drill as attached to the lower end of the drill stem showing the lower end of the core barrel in home position therein.

Referring now more particularly to the drawing wherein like numerals of reference designate similar parts in each of the figures, the numeral 1 designates a tubular drill stem whose sections are connected by suitable tool joints as 2 and attached to the lower end of the drill stem there is a drill 3 of any conventional construction and having an axial bore 4 through the lower end thereof for the inlet of the sample. Above its lower end the bore 4 is reduced in diameter forming the seat 5 to receive and support the lower end of the tubular core barrel 6. The lower end of the core barrel has sample retaining means

of any conventional construction. As shown the core retaining means comprise flexible fingers 7 whose lower ends are secured to the lower end of the core barrel and whose upper ends are curved inwardly.

There is a stem 8 whose lower end is enlarged forming the plunger 9 and the lower end of this plunger is connected to the upper end of said barrel preferably by threads. This plunger and the upper end of said barrel fit closely within the cylinder 10 whose upper end is screwed into the tool joint above. Beneath the upper end of the core barrel, said barrel is provided with the lateral openings 11 and within the barrel beneath said openings there is the annular valve seat 12 pinned in said barrel by the pin 13 or otherwise secured therein. The seat is normally closed by means of the upwardly opening ball valve 14.

The upper end of the stem 8 is enlarged and formed into an anchor 15, which is slidable in the trip sleeve 16. The lower end of this sleeve has the vertically elongated slots 17, 17 and a pin 18 extends through said anchor and its ends move in said slots. The upper end of the anchor 15 has an upwardly diverging bearing 19 which terminates in the transverse slot 20 through said anchor. There are the upwardly diverging flexible dogs 21, 21 whose lower ends are seated in said bearing and pinned therein by the pin 22 and whose upper ends diverge out through said slot 20. A coil spring 23 is located between the upper ends of said dogs.

The numeral 24 designates a rod whose lower end is formed into a plunger 25 which fits closely within the cylinder 26, which is attached to and depends from the tool joint above. The lower end of the plunger 25 is connected to the upper end of the sleeve 16 in any suitable manner, preferably by threads.

The upper end of the rod 24 is formed with a conical shaped head 27 for a purpose to be hereafter stated.

The lower end of the cylinder 26 is provided with an internal annular downwardly facing shoulder 28.

In carrying on drilling operations when it is desired to take the core, the core taking apparatus may be assembled as shown and a suitable grapple attached to the head 27 and the apparatus let down through the drill stem by means of a cable attached to the grapple. The lower end of the core barrel 6 will enter the enlarged upper end of the bore 4 and the plungers will

- enter the corresponding tool joints 2 and the drilling fluid above under pump pressure will force said plunger downwardly through the cylinders. While the coring apparatus is being lowered the pin 18 will hang on the lower ends of the slots 17 and if for any reason the lower end of the core barrel 6 should hang in the bore 4, the pressure of the fluid above the plunger 25 will force said plunger downwardly, 5 so lowered the pin 18 will hang on the lower ends of the slots 17 and if for any reason the lower end of the core barrel 6 should hang in the bore 4, the pressure of the fluid above the plunger 25 will force said plunger downwardly, 10 the sleeve 16 moving downwardly on the anchor 16 until the upper ends of the slots 17 engage the ends of the pin 18 and the stem 8 and barrel 6 will be forced further down until the core barrel is forced into home position whereupon the 15 plungers 25 and 9 will clear the respective outlet ports 29, 30 in the respective cylinders 26, and 10. Thereupon the pressure being released the pump will speed up indicating that the core barrel has landed on the seat 5.
- 20 While the coring apparatus is being lowered, the sleeve 16 will be in its upper position relative to the anchor 15 as hereinabove indicated and the spring dogs 21 will be thereby held in inner, or retracted, position, but when the sleeve 16 25 has been moved downwardly relative to the anchor 15, as above indicated, the slot 20 will align with the side slots 31, 31, through the sleeve 16 and the upper ends of the dogs 21, 21 will be projected through and beyond said slots 31 and 30 when said upper ends clear the shoulder 28 they will engage underneath the shoulder 28, to lock said core barrel in place.

The grapple may then be detached from the head 27 and the cable removed and drilling may then be proceeded with. A core or sample of the formation will enter the bore 4 and pass up into the core barrel above. Any liquid that may be in said core barrel will pass out through the seat 12 the valve 14 lifting for that purpose and 40 said liquid will pass on out through the openings 11. While the core is being taken drilling fluid will be forced under pressure down through the drill stem and will pass out through the channels 32, 32 which lead from said drill stem and 45 diverge through the drill 3 whereby flushing fluid is discharged in front of the respective cutter blades, or other cutters 33, 33.

The lower end of the drill may be formed with a pilot core bit 34 of any selected design. 50 When a core or sample has been taken the grapple may be again lowered as before and engaged over the head 27. An upward pull on the cable will cause the sleeve 16 to move upwardly 55 relative to the anchor 15 and the upward movement of said sleeve will retract the dogs 21 and disengage them from the shoulder 28 and the entire coring apparatus may then be withdrawn

to the ground surface for an inspection of the core.

The drawing and description discloses what is now considered to be a preferred form of the invention by way of illustration only while the broad principle of the invention will be defined by the appended claims. 5

What I claim is:

1. A core taking apparatus comprising a tubular drill stem having a drilling tool at the lower end thereof provided with an axial bore having an upwardly facing seat, spaced cylinders in the stem each having an inlet, a core barrel in the stem whose lower end is adapted to rest on said seat, spaced plungers connected to the barrel arranged to enter said cylinders as the barrel is lowered, said plungers forming means by which the barrel may be forced downwardly onto said seat by the pressure of the drilling fluid above and being arranged to clear said inlets when in 20 home position.

2. A sample taking apparatus comprising a tubular drill stem having upper and lower cylinders therein, a drill on the lower end of said stem having an inlet for the entrance of a sample, 25 a core barrel shaped to be lowered through said stem and cylinders into cooperating relation with the drill and into alignment with the inlet, plungers connected with said barrel and arranged to enter the respective cylinders as the barrel approaches its final position in the stem whereby pressure fluid in the stem above the plungers may be rendered effective to force the barrel downwardly to its final position, each cylinder having an outlet port and said plungers being positioned 30 to clear said ports to release said pressure when the barrel reaches said final position. 35

3. A sample taking apparatus comprising a tubular drill stem having upper and lower cylinders therein, a drill on the lower end of said 40 stem having an inlet for the entrance of a sample, a core barrel shaped to be lowered through said stem and cylinders into cooperating relation with the drill and into alignment with the inlet, plungers connected with said barrel and arranged to 45 enter and completely close the respective cylinders as the barrel approaches its final position in the stem whereby pressure fluid in the stem above the plungers may be rendered effective to force the barrel downwardly to its final position, said 50 plungers having a slip joint connection formed with relatively movable parts and interengaging means carried by said stem and connection respectively and normally locking the barrel in the stem, said locking means being arranged to be 55 released upon the relative movement of said parts.

FRED THRIFT.
